2,129,433

BLOW-OUT PREVENTER

John W. MacClatchie, Los Angeles, Calif., assignor to MacClatchie Manufacturing Company of California, Compton, Calif., a corporation of California

Application August 18, 1936, Serial No. 96,619

5 Claims. (Cl. 255—1)

This invention is a blowout preventer and has for its object to automatically align a packer of a blowout preventer with a well string which is to be packed off, irrespective of any misalignment of the well string in the well bore as may result from lateral drift of the well string or improper alignment or play in the rotary table.

It is a further object of the invention to mount the packing medium in a housing which is fixed against longitudinal displacement relative to the well casing on which the blowout preventer is mounted, but which is free for lateral play relative to the well casing so as to maintain alignment of the packing medium with the well string which it packs off.

It is a still further object of the invention to adapt the well string for rotation while packed off and at the same time provide for lateral adjustment of the packing medium so as to maintain proper alignment with the well string.

It is a still further object of the invention to rotate the packing medium with the well string which it packs off, with the rotating packing adapted to turn relative to a stationary element which is fixed to the well casing, and also adapted for lateral adjustment with relation to the stationary element.

Further objects of the invention will be readily understood from the following description of the accompanying drawings, in which:

Fig. 1 is a side elevation of the blowout preventer, partly in axial section.

Fig. 2 is a transverse section on the line 2—2 of Fig. 1.

Fig. 3 is a detail section on the line 3—3 of Fig. 2.

The blowout preventer is adapted for mounting on the casing 1 of a well so as to pack off a well string which extends through the blowout preventer and into the well casing; and in the illustrated embodiment of the invention the packing medium of the blowout preventer is adapted for rotation with the well string which may be a string of usual drill pipe, with the packing medium adapted to pack off and rotate with the usual kelly 2 of the drill string.

The blowout preventer includes a body 3 which is fixed to the well casing 1, preferably by a usual threaded connection 4, and which has a bore 5 forming a prolongation of the bore of the well casing, with lateral outlets 6 preferably communicating with the bore 5. A housing which is shown as a shell 7 and in which the packing medium is mounted is fixed against longitudinal displacement relative to the body 3 but is adapted

for lateral adjustment relative thereto so that the packing medium may accurately align with the drill string, irrespective of misalignment of the drill string in the well casing.

For this purpose the body 3 is radially flanged as shown at 8 and the shell 7 has a radial flange 9 which seats on the flange 8. Bolts 10 extend through these cooperating flanges, and the bolt holes 11 in one of the flanges are of appreciably greater diameter than the bolts to permit relative lateral movement of the elements 3—7. Packing 12 is preferably provided between the flanges 8—9, and is shown as U-packing having its end open to the well pressure in the bore 5 for operatively expanding the packing.

In the illustrated embodiment of the invention the packing medium which is mounted in the housing 7 is adapted to pack off and rotate with the kelly 2 and is therefore rotatable with relation to the stationary body 3, preferably by journaling the packing medium in the shell 7. As an instance of this arrangement the packing medium may be of the general type disclosed in my prior U. S. Patent No. 1,708,316 granted April 9, 1929, and includes a body 15 which is preferably anti-frictionally journaled in the shell 7 and packing 16—17 which fits in the bore of the body 15 around the kelly 2, the packing being preferably held in assembled relation by abutments 18—19 which preferably also form a rotary driving connection between the kelly 2 and the body 15.

For this purpose anti-frictional bearings 20—21 may be provided at the ends of the body 15, with the bearing 20 engaging the lower end 35 of the shell 7 and the bearing 21 engaged by a collar 23 which is threaded into the upper end of the shell; and anti-frictional bearings 24 may be provided at the periphery of the body 15 for engagement by the surrounding annular wall of 40 the shell 7.

A lubricant may be supplied to the bearing space between the body 15 and the shell 7 for lubricating the bearings 20—21—24, with escape of the lubricant preferably prevented by sealing means which include a packing 25 between the body 15 and the adjusting collar 23, and a packing 26 between the body 15 and the lower end of the shell 7. The packing 26 may be cup-packing which is fixed to the body 15 and which is adapted for expansion by well pressure from the bore 5 so as to seal against a collar 27 of the shell 7.

The bore 28 of the body 15 is preferably of greater diameter than the bore 5 so as to permit

lateral adjustment of the packing 16-17 with relation to the body 3 without the bore 28 obstructing the bore 5; and the packing assembly which includes the packing 16-17 and its abutments 18-19 is preferably removably mounted in the bore of the body 15.

For this purpose the abutment 18 preferably rests upon a tapering seat 30 which is formed in the bore of the body 15, with the bore of the 10 abutment of a configuration to fit that portion of a well string which is to be packed off, the said bore being square in cross-section in the illustrated embodiment of the invention wherein a kelly 2, which in accordance with usual practice 15 is square in cross-section, is adapted to be packed off. The abutment 19 is also received in the bore of the body 15 and is adapted for telescopic engagement by the abutment 18, with the packing 16, which has a square bore to fit snugly around 20 the square kelly 2, mounted in the bore of the abutment 19 so as to seat at one end against the abutment 18. The opposite end of this packing 25 may be engaged by a collar 31 which may be adjustably secured in the bore of the abutment 19 by means of a threaded retaining ring 32, and the collar 31 preferably has a square bore so that it also snugly engages the kelly 2.

The packing 17 is mounted between the abutments 18-19 at their outer peripheries so as to 30 engage the body 15, and the packing 16-17 is operatively expanded by adjustably telescoping the abutments 18-19. For this purpose the abutments 18-19 are connected by adjusting bolts 33 which also provide a rotary driving 35 connection between the telescopic abutments, and the telescopic abutments which are thus adapted for rotation with the kelly 2, in turn rotate the body 15, preferably by a splined engagement 34 between the abutment 19 and the bore of the 40 body 15.

The packing assembly 16-17-18-19 may be 45 releasably secured in the body 15 by holding means such as disclosed in my aforementioned U. S. Patent No. 1,708,316 granted April 9, 1929. 50 As an instance of this arrangement a sleeve 36 is threaded onto the shell 1, and latches 37 are pivoted to the sleeve as shown at 38. Anti-friction rollers 39 are journaled on the latches, and when the latches are swung to operative position 55 as shown in the drawings the rollers 39 longitudinally align with the abutment 19 so that by screwing the sleeve 36 downwardly on the shell 1, the rollers 39 may be brought into engagement with the abutment 19. The sleeve 36 may be locked in adjusted position by set screws 40.

When the latches 37 are swung on their pivots 38 to their inoperative position, the rollers 39 clear the abutment 19 so as to permit removal and replacement of the packing assembly; and 60 the latches are normally held in locking position but are adapted to be swung to releasing position by means of a ring 42 which is journaled on the sleeve 36. The pivoted latches 37 have projections 43 which are received in cam grooves 44 in the ring 42, so that when the ring is turned 65 in one direction with relation to the sleeve 36 the cam surfaces of the grooves engage the projections 43 as shown at Fig. 3 and thereby swing and retain the latches 37 in their operative position, while turning the ring 42 in the opposite direction with relation to the sleeve 36 causes the cam surfaces of the grooves 44 to longitudinally shift the projections 43 so as to swing and retain the latches 37 in their inoperative position. 70

75 A manual control, preferably operable from a

remote point, is provided for turning the ring 42 in either direction for projecting or retracting the latches 37, and for this purpose the outer periphery of the ring 42 may form grooves 45 for a pair of operating cables (not shown) which are connected to the ring 42 and wound thereon in opposite directions, so that a pull on one of the cables operatively projects the latches 37, while a pull on the other cable inoperatively retracts the latches. 10

The invention as thus described provides for conveniently mounting a blowout preventer on well casing so that its packing medium may provide an efficient pack off for a well string which extends through the blowout preventer and into 15 the well casing, the packing medium being fixed against longitudinal displacement but laterally adjustable with relation to the well casing so as to properly align with the well string, and the packing medium being preferably adapted for 20 rotation with the well string so as to form a rotating blowout preventer, with the rotatable packing medium freely laterally adjustable with relation to a stationary part of the blowout preventer which is mounted on the well casing. 25

I claim:

1. In combination, cooperating elements one of which is a stationary member adapted for mounting on a well casing and the other of which is a shell, a mounting for said cooperating elements 30 securing said elements against longitudinal displacement but adapted for lateral and rotational adjustment, and a rotatable packer mounted in said shell, said packer having an opening therethrough for a well string and adapted to rotate 35 with said well string, means expensible by pressure fluid for packing off said shell against said stationary member and for packing off said rotatable member against said shell.

2. In combination, cooperating elements one of 40 which is a stationary member adapted for mounting on a well casing and the other of which is a shell, a mounting for said cooperating elements securing said elements against longitudinal displacement but adapted for lateral and rotational 45 adjustment, and a rotatable packer mounted in said shell, said packer having an opening therethrough for a well string and adapted to rotate with said well string, means expansible by pressure fluid for packing off said shell against said stationary member and for packing off said rotatable member against said shell, latches mounted on said shell adapted for projection to engage the packer and prevent its longitudinal displacement. 50

3. In combination, cooperating elements one of which is a stationary member adapted for mounting on a well casing, and the other of which is a shell, a mounting for said cooperating elements securing said elements against longitudinal displacement but adapted for lateral and rotational adjustment, and a rotatable packer mounted in said shell, said mounting including anti-frictional 6 bearings and means for retaining a lubricant at said bearings, said packer having an opening therethrough for a well string and adapted to rotate with said well string, means expansible by pressure fluid for packing off said shell against said stationary member and for packing off said rotatable member against said shell. 6

4. In combination, a rotatable packer having an opening therethrough for a well string for packing off said string and arranged to rotate with said string, cooperating elements one of which is a stationary member arranged for 7

mounting on a well casing and the other of which is a shell in which the packer is rotatably mounted, a mounting for said cooperating elements positively securing said elements in position and arranged for lateral adjustment, whereby axial displacement of the well string in the casing may be compensated and the packer and shell concentrically aligned with said well string, and means expandible by pressure fluid for packing off said shell against said stationary member and for packing off said rotatable member against said shell.

5. In combination, a rotatable packer having an opening therethrough for a well string for packing off said string and arranged to rotate with said string, cooperating elements one of

which is a stationary member arranged for mounting on a well casing and the other of which is a shell in which the packer is rotatably mounted, a mounting for said cooperating elements positively securing said elements in position and arranged for lateral adjustment, whereby axial displacement of the well string in the casing may be compensated and the packer shell concentrically aligned with said well string, means expandible by pressure fluid for packing off said shell against said stationary member and for packing off said rotatable member against said shell, and means carried by the shell and engageable with the packer for preventing longitudinal displacement of the latter relative to the shell. 15

JOHN W. MACCLATCHIE.
